UNITED STATES PATENT OFFICE.

JACOB W. LATTIG, OF WEST BETHLEHEM, AND CHARLES LANE GOODRUM, OF PHILADELPHIA, PENNSYLVANIA, AND EDWARD E. CLEMENT, OF WASHINGTON, DISTRICT OF COLUMBIA.

TELEGRAPHIC SYSTEM.

No. 820,652.

Specification of Letters Patent.

Patented May 15, 1906.

Application filed June 9, 1903. Serial No. 160,750.

To all whom it may concern:

Be it known that we, JACOB W. LATTIG, residing in West Bethlehem, Lehigh county, and CHARLES LANE GOODRUM, residing in Philadelphia, county of Philadelphia, Pennsylvania, and EDWARD E. CLEMENT, residing in Washington, District of Columbia, citizens of the United States, have jointly invented a new and useful Telegraphic System, of which 10 the following is a specification.

Our invention relates to telegraphic systems, and more particularly to those in which lines are employed to serve "way-stations." Such lines usually pass through all the stations in series, all instruments being included directly therein. Circuits of this kind are frequently employed in railway service for communicating between train - despatchers and line operators, as well as in ordinary 20 commercial work. We have discovered a way in which we can double the capacity for transmission over such a line and incidentally attain a great many advantages of value in themselves. Thus it has heretofore not been 25 economically possible to maintain regular telegraphic service on moving trains, this resulting from the fact that ordinary telegraphic messages passing to all the stations reached every station and the only way any 30 operator could tell what messages were intended for him would be by constant listening. This meant the use of a telephone-receiver, particularly because the impulses inductively received on a moving train were 35 very weak. For these reasons it will be observed that to give continuous service it would require the entire time of one man, and this would mean the addition of a telegraph operator to every train crew, with the 40 likelihood that outside of the train-orders not enough business would pass through his hands even on long runs to pay more than a small fraction of his salary and expenses.

In order to make train telegraphy commercially feasible, it must be possible to call up the train when wanted and only for train-despatches, giving a signal that will be loud enough or conspicuous enough to attract the attention of the operator while engaged in 50 other duties, and the signals received must be of such a nature that they can be recorded in the ordinary way, so that operators may be employed who are not highly-skilled experts,

such operators being frequently good transmitters but very slow receivers. Thus a 55 railroad would be enabled to make the telegraph operator a regular member of the train crew, such as the baggage-master, and only so much of his time will be taken from his regular duties as may be required by messages sent to and from his own train.

Our invention is not limited to train service, being applicable to any line and particularly any way-station line.

It consists, essentially, in the application 65 of coherers in the manner disclosed by Edward E. Clement in Patents Nos. 719,998 and 719,999, issued February 10, 1903, to systems of the character described, using superposed currents or impulses of suitable 70 character to operate the coherers, but of unsuitable character to operate the ordinary relays at the way-stations on the line.

Our invention is fully described herein-after and illustrated in the accompanying 75 drawing, in which the figure is a diagram of a system embodying our invention.

Referring to the drawing, 1 is a line-circuit extending through three way-stations U, V, and W, passing in series through the relays 80 R, R', and R'' and the normally closed keys K, K', and K''. These keys are shunted by circuits 2, 3, and 4, containing condensers C, C', and C''. The relays R, &c., through their armatures r, r', and r'', respectively, control 85 sounders or recorders, (indicated at S, S', and S''), current for these being supplied by the local batteries b, b', and b''. When a signal is to be transmitted from one of these stations to any other, its key K is opened at a time 90 when the relay is not working, and by then manipulating it all the relays along the line may be effected, current being supplied thereto by the generators B B'. The currents used over the circuit 1 are direct currents entirely, which are passed through the relays 95 R, &c., but do not penetrate the condenser-circuits 2, 3, and 4. These condensers, however, make the line practicable for another class of currents, which we superpose on the 100 line, which may be alternating currents or high frequency broken or periodic currents of any kind, such as the succession of impulses from an induction-coil having an interrupter in its primary. In addition to the stations 105 U, V, and W we carry the line to stations X,

Y, and Z. This may be by means of a conductive connection or an inductive connection through coils or condensers, as shown, and the stations X, Y, and Z may be stationary or they may be movable, like cars on a railroad. In the latter case the connections would be inductive, preferably, the instruments in the car being connected to the car-roof or other extended metal coating and the communication between that and the line along the tracks being by electrostatic effect. It is quite feasible to have the car provided with a brush to travel on a conductor rail or wire, however, and in such case the connection would be conductive and more positive, also more expensive.

From the line 1 taps 5, 6, and 7 are taken off to the stations X, Y, and Z, respectively, either inductive or conductive, as stated.

- 20 The wire 5 passes to a relay R^3 , thence to the secondary winding i of an induction-coil I, and thence to ground. A branch 50 is taken around the relay R^3 and includes the coherer M. The relay R^3 has its armature included in and controlling a local circuit 500, in which are connected in parallel the recorder or sounder S^3 and the coherer-tapper T with a local battery b^3 .

At stations Y and Z the parts and connections are the same as at station X, the lettering being the same with different exponents to distinguish the station.

The operation of our system is as follows: Messages are sent over the main circuit 1 in the usual manner by means of makes and breaks in the direct current supplied by the generators B and B', for such currents the path being closed only through the relays and keys. This service goes on without reference to that between stations X, Y, and Z, and calls are interchanged between those stations whether the line is busy or not. If X desires to call Y—say the train-despatcher desires to call train No. 147—he uses key K^3 , listening first, as in every way-station system, to see if the line is in use by station Y or Z. The key K^3 in closing starts current from battery b^6 through the circuit 8 and the primary of induction-coil I, whereupon the secondary i sends to line a rapidly-alternating set of impulses, due to the breaks in the primary caused by the vibrating armature or other circuit-breaker in the circuit 8. The path for these impulses is through condenser, capacity, or conductor (as the case may be) C^3 to line 1 and then over the same to all the stations of the coherer type, going by preference through the condensers C, C', and C² and not through the relays R, R', or R² on account of their high inductance. Thus no disturbance is produced in the relay-circuits. At each station Y or Z this alternating current comes to ground through the coherer and the secondary i , the first impulse or set of impulses causing the coherer to set, its re-

sistance to be lowered, and the local circuit composed of conductors 6 and 60 or 7 and 70 to be closed through its battery b^{10} or b^{11} . As this local circuit includes the relay R^4 or R^5 , the armature thereof is drawn up and the circuit 600 or 700 is closed, causing current from battery b^4 or b^5 to affect the recorder or sounder S^4 S^5 and the tapper T' T² to restore the coherer to its usual condition of high resistance. Operator at station X can thus call either of the other stations and after receiving an answer can transmit the message, or the call can be made, and then if a recorder is used at each station the message can be sent along and being recorded can be read and transcribed afterward.

Our invention solves a serious problem in railway telegraphy and is useful in many other fields.

We are aware that many changes can be made in the matter of details, and all such we include within the scope of our claim. For instance, self-restoring or what are called "self-decohering" coherers can be used, when the tapper T can be dispensed with, alternating current can be used from a generator instead of the induced current from an induction-coil, &c. The coherers can be of any suitable and desired form, those we have found preferable being of the type designed by Professor Oliver Lodge, which are well known, consisting of tubes of filings or other granulated material. These coherers can also be replaced by other sensitive devices without departing from the invention, the gist of which is to normally hold the stations out of circuit in an operative sense, so that ordinary signals do not pass, but to bring them in for calling purposes at will. We shall use the term "sensitive resistance device" in the claim to designate the coherer or any equivalent device useful in our system. We shall use the words "opaque" and "transparent" also in the sense in which they are employed in the patents to Clement above referred to—that is, opaque as stopping the current from passing and transparent as permitting it to pass. We shall use the expression "a connection from each station to line" or its equivalents as meaning any sort of connection by which the impulses to affect the coherers or their equivalents may be passed. Thus the line-wire along the track might receive the same sort of waves as those used in so-called "space telegraphy," broadly serving as a continuous antenna, and in such case the ears of a train carrying the coherers might be fitted with wires to receive the wave impulses similar to the vertical wires similarly employed. In fact, if electrostatic effects are to be assisted by Hertz waves no receiving wires need be provided, or very short ones, a surface being sufficient.

In using this system for train-orders it seems that the best and most reliable method

would be to keep a constant succession of impulses normally on the line, stopping them in a predetermined manner to call. Any derangement would thus announce itself, and that certainty would be attained that is so necessary in railway matters. We shall include this in our claim, as it reverses the usual mode of operation and is a valuable feature.

At each of the stations X and Z we have shown a telephone O in a branch wire 11. After a station has been called the telephones can be used in the ordinary way, condensers C², &c., and C³, &c., passing the telephonic currents perfectly. This is also feasible on moving cars by induction or otherwise, and it should be stated that in such case the grounds 12 would be made through the car-wheels.

Having thus described our invention, what we claim, and desire to secure by Letters Patent, is—

In a system of railway communication, the combination with the following instrumentalities: a continuous conductor and a line of rails in proximity thereto, means to produce rapidly-changing electromotive forces in said conductor, a vehicle adapted to move

upon said rails, a normally open signal-circuit containing a battery and a signal-receiving device, together with a coherer or similar radiosensitive device, a conducting body mounted upon said vehicle and moving therewith in constant inductive relation to the fixed conductor, a connection from said body to the radiosensitive device and to ground, a telephone instrument on the vehicle also connected to said body and to ground, and means carried on the vehicle to impress rapidly-changing electromotive forces on said body, whereby the occupants of the vehicle may call or be called by means of the coherer and signal device, and may thereafter communicate by means of the telephone while the vehicle is in motion, substantially as described.

In witness whereof we have hereunto signed our names in the presence of two subscribing witnesses.
